United States Patent

Des. 241,255
Patented Aug. 31, 1976

241,255

PET FEEDING TRAY OR SIMILAR ARTICLE

James D'Angelo, 8045 W. Potomac Ave.,
Milwaukee, Wis. 53218

Filed Apr. 14, 1975, Ser. No. 567,698

Term of patent 14 years

Int. Cl. D30—03

U.S. Cl. D30—13

FIG. 1 is a perspective view of a pet feeding tray or similar article showing my new design;

FIG. 2 is a top plan view thereof;

FIG. 3 is a right side elevational view thereof;

FIG. 4 is a front elevational view thereof; and

FIG. 5 is a rear elevational view thereof.

I claim:

The ornamental design for a pet feeding tray or similar article, as shown.
